H. L. Karr
Attest.

UNITED STATES PATENT OFFICE.

FRANCIS KARR, OF HOLLAND, MICHIGAN.

CUSHION.

Application filed September 16, 1919, Serial No. 324,151. Renewed February 17, 1923.

To all whom it may concern:

Be it known that I, FRANCIS KARR, a citizen of the United States, and resident of Holland, county of Ottawa, State of Michigan, have invented certain new and useful Improvements in Cushions, of which the following is a specification, and which are illustrated in the accompanying drawings, forming a part thereof.

10 The invention relates to cushions for various uses and is illustrated as taking the form of a pillow. It consists broadly of a resilient body formed of wire fabric and having the form of a cylinder or modification thereof, and being enclosed in an enveloping pad. Other features of the invention will hereinafter appear.

15 The invention is illustrated in the accompanying drawings, in which;—

20 Fig. 1 is a detail in perspective of the resilient fabric;

25 Fig. 2 is a view in perspective of the cushion taking the form of a pillow, a portion being broken away to show the internal construction;

Fig. 3 is a cross sectional view of the pillow shown in Fig. 2.

The resilient element of the cushion, a detail of which is shown in Fig. 1, consists of a plurality of helical coils of spring wire arranged in two sets of parallel rows which intersect preferably obliquely, forming a fabric having a diamond shaped mesh. At their points of intersection the coils 10, 11, are interlocked as by a screw action, a plurality, as shown two, of the turns as 12, 13, of the coil 10 enclosing a corresponding number of the turns as 14, 15, of the coil 11. By reason of this plural locking of the two

40 sets of coils, the fabric maintains substantially the original form of its mesh even under tension in any direction. This fabric may be woven flat and then given the desired form, the meeting ends being secured together, or, and preferably it is, formed as a hollow body 16, without seam or joint, the several coils extending from end to end of the body and each following a spiral direction as indicated in Fig. 2.

50 The hollow body may have the form of a cylinder or may be flattened to the extent desired for the particular service for which it is intended. When it is to be used as a pillow it is given the oval form shown in Fig.

3. This hollow body is enveloped in a pad 55 17 of a textile fabric or felt, of such thickness as may be required for comfort.

When the cushioning is formed of light wire, stay cords 18, as many being employed as seem advisable, are preferably secured 60 across the interior of the cushion, to limit the distortion from its normal form. When the cushion is to be used as a pillow and is given the oval form such stays located on its longest diameter prevent distortion and 65 limit the yielding to pressure to the flexure of the longer sides either wholly or partially depending upon the character of the stays as to elasticity or length. This cord may be of any suitable material such as string, wire, or 70 a chain, and may or may not be elastic.

Such pillows are exceedingly comfortable to the user, being soft but comparatively firm and do not become heated.

The invention may be readily applied to 75 cushions for chairs, chair seats and arms or may be used in mattresses.

The word "cylinder" as employed in the appended claims is not intended to have the restricted and technical meaning as it is defined in the dictionaries, but to include other than forms which are circular in cross section, such as an oval.

I claim as my invention—

1. A cushion comprising a cylindrical resilient element formed of helical coils of spring wire, the coils being arranged in two sets, those of each set being parallel and the coils of each set crossing those of the other set obliquely and being interlaced therewith, 80 two turns of each coil enclosing two turns of the other.

2. In a cushion, in combination, a hollow cylindrical element, the walls of which comprise a fabric of spirally arranged helical coils extending in a plurality of directions, a plurality of the turns of each helical passing through turns of the other helical at intersections of helicals and an enveloping pad.

3. A cushion comprising a hollow cylindrical element the walls of which comprise a fabric of spirally arranged helical coils extending in a plurality of directions, a plurality of the turns of each helical passing through turns of the other helical at intersections of helicals.

FRANCIS KARR.
